ADIPONITRILE PROCESS

Manuel M. Baizer, St. Louis, Mo., Charles R. Campbell, Pensacola, Fla., Robert H. Fariss, St. Louis, Mo., and Robert Johnson, Pensacola, Fla., assignors to Monsanto Company, a corporation of Delaware

Filed Feb. 1, 1963, Ser. No. 255,586
10 Claims. (Cl. 204—73)

The present invention relates to a process of electrolytically hydrodimerizing acrylonitrile to adiponitrile in a salt catholyte of a divided cell employing acid anolyte.

General conditions which are effective for electrolyzing acrylonitrile to adiponitrile are described in co-pending applications of one of us, Ser. No. 228,740, filed October 5, 1962, and now abandoned, such application being a continuation-in-part of Ser. No. 145,482, filed October 16, 1961, and now abandoned; and of Ser. No. 75,130, filed December 12, 1960, and now forfeited, the aforesaid applications having been abandoned or forfeited in favor of continuation-in-part application Ser. No. 333,647, filed December 26, 1963. The present invention is concerned with the employment of acid anolyte in such a process, the conditions of such employment and the advantages resulting therefrom.

The figure of the drawing is an illustration of an acrylonitrile electrolysis system in which the anolyte and catholyte are separately circulated through the electrolysis cell which is illustrated in cross-section.

There are certain advantages in employing a divided cell in the electrolytic hydrodimerization of acrylonitrile. For one thing, it is desirable to keep the acrylonitrile away from the anode where it would be subject to oxidation. Similarly, many of the most suitable salt electrolytes for the hydrodimerization of acrylonitrile, for example quaternary ammonium aromatic sulfonates, are subject to decomposition at the anode. Such salts are particularly suitable as they have very negative cathode discharge potentials and are therefore unlikely to interfere with the hydrodimerization of acrylonitrile at the cathode which occurs at about —1.75 to about —1.9 volts (vs. a saturated calomel electrode). However, the presence of such salts or the anodic oxidation products of such salts and acrylonitrile in the anolyte can cause severe anode corrosion. A salt solution is used for the electrolysis because of the tendency of acrylonitrile to polymerize when electrolyzed under acid conditions. It is generally desirable to have the catholyte pH in the range of about 7 to about 9.5 or 10.

The term "consisting essentially of" as employed herein with respect to the solutions electrolyzed is intended to leave the solutions open to addition of other components which do not change the basic nature of the solutions with respect to the electrolytic hydrodimerization being conducted therein.

There are many advantages in the use of an acid anolyte in the hydrodimerization of acrylonitrile. Relatively speaking, an aqueous solution containing a quaternary ammonium salt and acrylonitrile tends to have a high electrical resistance. The overall resistance of the cell can be considerably lessened, therefore, if a mineral acid rather than a quaternary ammonium salt solution is utilized as anolyte. Mineral acids, e.g., sulfuric acid, have the additional advantage of being inexpensive and readily available. Phosphoric acid and other mineral acids can be employed, as can organic sulfonic acids, e.g., benzene or toluene sulfonic acids. Sulfuric acid is definitely preferred as its use minimizes corrosion problems and the oxygen produced at the anode in such acid does not cause any special difficulties. During electrolysis in a divided cell, alkalinity ordinarily increases in the catholyte. While hydrodimerization of acrylonitrile

2

could successfully be conducted for some period of time without provisions to counteract the alkalinity, it is apparent that eventually the build-up of hydroxyl ions in the catholyte would be such as to cause undesirable side-reactions to predominate. Control of alkalinity becomes particularly necessary if the electrolytic hydrodimerization is conducted in a continuous manner with continuous or intermittent addition of nitrile and removal of product, while the electrolyte itself stays in the cell or is recycled to the cell. When a divided cell utilizes a cationic diaphragm and acid is employed as anolyte, the alkalinity of the catholyte depends upon the rate at which ions or molecules move across the diaphragm relative to the rate of generation of hydroxyl ion by the electrolysis; during electrolysis the hydrogen ions are transported through the diaphragm in an amount approximately equivalent to hydroxyl generation at the cathode. This is accompanied by some diffusion of ions and molecules through the diaphragm as a result of concentration differences.

20 In accordance with the present invention it has been found that in the electrolysis of acrylonitrile control of catholyte alkalinity can very suitably be effected by employing a mineral acid anolyte in conjunction with a cation exchange membrane separating the anolyte from the catholyte.

25 In the past various electrolysis reactions for reducing or otherwise altering organic compounds have been known. In general, however, such reactions have had the disadvantage of being of small scale and low velocity and requiring careful control of many conditions. Quite often such reactions could not be "scaled-up" by using high current densities to give practical production rates and therefore remained laboratory curiosities. In contrast, the present process operates very effectively at current densities of greater than 10 amperes/square decimeter of cathode surface, and the most suitable densities may be in the range of 15 to 20 to 40 or 50 amperes/square decimeter and higher, even up to 100 or more amperes/square decimeter, and it is further possible to use cells 30 having a large effective electrode area, whether in a single set of electrodes or in a series of electrodes. Thus in commercial practice it is probable that individual cells will draw at least 20 to 30 amperes, most likely more than 100 amperes, and cells drawing more than 1000 amperes are contemplated. For reasons of economics and to make practical use of such current densities without necessitating prohibitively high cell voltages, it is essential to have fairly low resistance in the cell as obtainable by utilizing fairly high concentrations of the electrolyte 35 salt and a relatively narrow gap between the electrodes, e.g., no more than one-half inch, and preferably of the order of one-fourth inch or smaller. Applied voltages of 5 to 20 volts for current densities of 15 to 40 amperes/dm.² are suitable, and it is preferable, in this range as well as at higher densities that the applied voltage have a numerical value no greater than one-half of the numerical value of the current density (in amperes/dm.²). Various power sources are suitable for use in the present 40 invention, particularly any efficient sources of direct current, and, if desired, various known means of varying the applied potential to regulate the current density and the cathode potential can be employed, for example the means described in Metcalf et al., U.S. Patent No. 2,835,631, issued May 20, 1958, the disclosure of which is incorporated herein by reference. If desired alternating current can be superimposed on the direct current applied to the cell.

45 In carrying out the present invention, the acid employed as anolyte will have a normality such that enough hydrogen ions migrate to the catholyte to counteract the hydroxyl ions generated at the chosen current density.

3

Example

Acrylonitrile was hydrodimerized in a divided cell with acid anolyte in a number of runs under comparable conditions except that the current density was varied and the anolyte normality was correspondingly adjusted to control catholyte pH, with results as follows:

Run	Current Density, amps./dm. ²	Anolyte Normality	Catholyte pH
1	15	0.58	9.0
2	20	0.61	8.7
3	25	0.80	8.9
4	30	0.98	8.7
5	40	1.08	8.7

It is thus demonstrated that as current density is increased, the anolyte normality can be increased to control the catholyte pH and maintain it within a selected range, e.g., 7 to 9.5. All of the runs were successfully conducted for a number of hours with the acrylonitrile yields constituting better than 90% of product. It was not necessary to add any acid or other material to the catholyte during the runs to control the pH.

The foregoing runs were made with sulfuric acid as anolyte and employing a cationic membrane as the cell divider, the particular membrane being a cationic membrane comprised of a sulfonated styrene-divinyl benzene polymer supported upon a glass fiber base. The linear flow rate of the catholyte along the cathode surface was approximately 1.5 ft./sec.

The electrolyses were conducted in the system illustrated in the figure of the drawing.

The electrolysis takes place in electrolysis cell 1 in which a cathode plate 2 and a diaphragm 3 with the other walls of the completely enclosed cell chamber form a cathode compartment and the said diaphragm 3 and anode plate 4 form a separate anode compartment. The cathode 2 is connected to the negative terminal of a source of direct current, while the anode 4 is connected to the positive source of such current, and the cathode and anode are clamped in juxtaposition but separated by insulating gasketing material. In operation, acrylonitrile is fed through pump 5 and the salt solution through pump 6 to the catholyte recirculating pump 7 and then through an aperture in the cathode plate 2, through the cathode compartment and out another aperture in the cathode plate to the catholyte reservoir 8. The catholyte reservoir is provided with means (not illustrated) such as a gravity overflow system to discharge part of the catholyte, and means are also available to heat the catholyte in the reservoir if necessary. A pH meter 9 is hooked into the catholyte recirculation line 10, and a water-jacketed heat exchanger 11 is hooked across the recirculation pump to permit cooling of the catholyte if necessary. The anolyte is made up by feeding water and acid to the anolyte reservoir 12 from which it is fed through a water-jacketed heat exchanger 13 to the anolyte recirculating pump 14, thence through an aperture in the anode plate 4 and through the anode chamber to return to the anolyte reservoir 12. The anolyte reservoir is equipped with a water-jacketed condenser 15 to permit oxygen or other gases to escape from the anolyte. There is a differential manometer 16 connected across the catholyte and anolyte inlets of cell 1 to permit equalization of pressures on the two sides of diaphragm 3. The cathode was lead and the anode, platinum on titanium; other electrode materials are suitable, for example, mercury or various lead alloys as cathode, and lead or lead alloys as anode. It will be understood that the electrodes are in actual contact, i.e., solid-liquid contact, with the catholyte and anolyte and are not separated therefrom by an air gap or otherwise.

The catholyte employed in the runs was a 60% by weight concentration of tetramethylammonium toluene

4

sulfonate in water, and the acrylonitrile was provided in an amount to constitute 33% by weight of the catholyte. While there will be some variation with the ion exchange membranes employed and other electrolysis conditions, it will generally be desirable to have the acid anolyte normality have a value in the range of about 0.02 to 0.06 times the current density (in amperes/dm.²); for example, about 0.03 times the current density, in order to maintain the catholyte pH relatively constant. For example, normalities of about 0.4 to 1.2 are suitable for current densities of 15 to 40 amperes/dm.² of cathode area. In general the acid employed as anolyte will be fairly dilute, particularly when a strong mineral acid is employed, e.g., from 0.05 to 5 or 10% by weight acid based on the weight of acid and water, and seldom more than 20% by weight on the same basis. Sulfuric acid is very suitable for use in the present invention, and such concentrations of sulfuric acid can suitably be employed, and are practical and useful from the viewpoint of conductivity and low anodic corrosion, as well as pH control. Other strong acids, e.g., those having relatively high ionization constants, such as greater than 10^{-3} at 25° C., can suitably be employed in such concentrations.

Numerous electrolyte salts are already known and suitable electrolyte salts can be selected in the light of the present disclosure for use in the catholyte in the present invention. In general it will be desirable to avoid overly acidic or overly basic salts in view of the pH considerations discussed herein, and ordinarily salts of strong bases will be employed, particularly salts of strong bases and strong acids.

Among the salts which can be employed the amine and quaternary ammonium salts are generally suitable, especially those of sulfonic and alkyl sulfonic acid. Such salts can be the saturated aliphatic amine salts or heterocyclic amine salts, e.g., the mono-, di- or trialkylamine salts, or the mono-, di- or trialkanolamine salts, or the piperidine, pyrrolidine or morpholine salts, e.g., the ethylamine, dimethylamine or triisopropylamine salts of various acids, especially various sulfonic acids. Especially preferred are aliphatic and heterocyclic quaternary ammonium salts, i.e., the tetraalkylammonium or the tetraalkanolammonium salts or mixed alkyl alkanol ammonium salts such as the alkyltriakanolammonium, the dialkyldialkanolammonium, the alkanotrialkylammonium or the N-heterocyclic N-alkyl ammonium salts of sulfonic or other suitable acids. The saturated aliphatic or heterocyclic quaternary ammonium cations in general have suitably high cathode discharge potentials for use in the present invention and readily form salts having suitably high water solubility with anions suitable for use in the electrolytes employed in the present invention. The saturated, aliphatic or heterocyclic quaternary ammonium salts of such acids are therefore in general well adapted to dissolving high amounts of olefinic compounds in their aqueous solutions, i.e., hydro-tropic salts, and to effecting reductive couplings of such olefinic compounds. It is understood, of course, that it is undesirable that the ammonium groups contain any reactive groups which might interfere to some extent with the reductive coupling reaction. In this connection it should be noted that aromatic unsaturation as such does not interfere as benzyl substituted ammonium cations can be employed (as also can aryl sulfonate anions).

Among the anions useful in the electrolytes, the aryl and alkaryl sulfonic acids are especially suitable, for example, salts of the following acids: benzenesulfonic acid, o-, m- or p-toluenesulfonic acid, o-, m- or p-ethylbenzenesulfonic acid, o-, m- or p-cumenesulfonic acid, o-, m- or p-tert-amylbenzenesulfonic acid, o-, m- or p-hexylbenzenesulfonic acid, o-xylene-4-sulfonic acid, p-xylene-2-sulfonic acid, m-xylene-4 or 5 sulfonic acid, mesitylene-2-sulfonic acid, durene-3-sulfonic acid, pentamethylbenzenesulfonic acid, o-dipropylbenzene-4-sulfonic acid, al-pha- or beta-naphthalenesulfonic acid, o-, m- or p-bi-

phenylsulfonic acid, and alpha-methyl-beta-naphthalenesulfonic acid. Alkali metal salts are useful with certain limitations, and the alkali metal salts of such sulfonic acids can be employed, i.e., the sodium, potassium, lithium, cesium, or rubidium salts such as sodium benzene-sulfonate, potassium p-toluenesulfonate, lithium o-bi-phenylsulfonate, rubidium beta-naphthalenesulfonate, cesium p-ethylbenzenesulfonate, sodium o-xylene-3-sulfonate, or potassium pentamethylbenzenesulfonate. The salts of such sulfonic acids may also be the saturated, aliphatic amine or heterocyclic amine salts, e.g., the mono-, di- or trialkylamine salts, or the mono-, di or trialkanol-amine salts, or the piperidine, pyrrolidine, or morpholine salts, e.g., the ethylamine, dimethylamine or triisopropyl-amine salt of benzenesulfonic acid or of o-, p- or m-toluenesulfonic acid; the isopropanolamine, dibutanolamine or triethanolamine salt of o-, p- or m-toluenesulfonic acid or of o-, p-, or m-biphenylsulfonic acid; the piperidine salt of alpha- or beta-naphthalenesulfonic acid or of the cumenesulfonic acids, the pyrrolidine salt of o-, m-, or p-amylnenesulfonate; the morpholine salt of benzene-sulfonic acid, of o-, m- or p-toluenesulfonic acid, or of alpha- or beta-naphthalenesulfonic acid, etc. In general, the sulfonates of any of the ammonium cations disclosed generically or specifically herein can be employed in the present invention. The aliphatic sulfonates are prepared by reaction of the correspondingly substituted ammonium hydroxide with the sulfonic acid or with an acyl halide thereof. For example, by reaction of a sulfonic acid such as p-toluenesulfonic acid with a tetraalkylammonium hydroxide such as tetraethylammonium hydroxide there is obtained tetraethylammonium p-toluenesulfonate, use of which in the presently provided process has been found to give very good results. Other presently useful quaternary ammonium sulfonates are, e.g., tetraethylammonium o- or m-toluenesulfonate or benzenesulfonate; tetraethylammonium o-, m- or p-cumenesulfonate or o-, m-, or p-ethylbenzenesulfonate; tetraethylammonium benzene-sulfonate, or o-, m- or p-toluenesulfonate; N, N-di-methyl-piperidinium o-, m- or p-toluenesulfonate or o-, m- or p-biphenylsulfonate; tetrabutylammonium alpha- or beta-naphthalenesulfonate or o-, m- or p-toluenesulfonate; tetrapropylammonium o-, m- or p-amylnenesulfonate or alpha-, ethyl- beta-naphthalenesulfonate; tetraethanolammonium o-, m- or p-cumenesulfonate or o-, m- or p-tulenesulfonate; tetrabutanolammonium benzenesulfonate or p-xylene-3-sulfonate; tetrapentylammonium o-, m- or p-toluenesulfonate or o-, m- or p-hexylbenzenesulfonate, tetrapentanolammonium p-cumene-3-sulfonate or benzene-sulfonate; methyltriethylammonium o-, m- or p-toluenesulfonate or mesitylene-2-sulfonate; trimethylethylammonium o-xylene-4-sulfonate or o-, m- or p-toluenesulfonate; triethylpentylammonium alpha- or beta-naphthalenesulfonate or o-, m- or p-butylbenzenesulfonate, trimethylethanolammonium benzenesulfonate or o-, m- or p-toluenesulfonate; N,N-diethylpiperidinium or N-methyl-pyrrolidinium o-, m- or p-hexylbenzenesulfonate or o-, m- or p-toluenesulfonate, N,N-di-isopropyl or N,N-dibutyl-morpholinium, o-, m- or p-toluenesulfonate or o-, m- or p-biphenylsulfonate, etc.

The tetraalkylammonium salts of the aryl or alkaryl-sulfonic acids are generally preferred for use as the salt constituents of the electrolysis solution because the electrolyses in the tetraalkylammonium sulfonates are exclusively electrochemical processes.

Among the ammonium and amine sulfonates useful as electrolytes in the present invention are the alkyl, aralkyl, and heterocyclic amine and ammonium sulfonates, in which ordinarily the individual substituents on the nitrogen atom contain no more than 10 atoms, and usually the amine or ammonium radical contains from 3 to 20 carbon atoms. It will be understood, of course, that di- and poly-amines and di- and poly-ammonium radicals are operable and included by the terms amine and ammonium. The sulfonate radical can be from aryl, alkyl, 75

alkaryl or aralkyl sulfonic acids of various molecular weights up to for example 20 carbon atoms, preferably about 6 to 20 carbon atoms, and can include one, two or more sulfonate groups.

Various other cations are suitable for use in the present invention, e.g., tetraalkyl-phosphonium and tri-alkylsulfonium cations, particularly from sulfonate salts formed from sulfonic acids as described above. Similarly, other anions can be selected from alkylsulfonates and anions of other acids. Further guides to the choice and use of the electrolyte salt are found in the aforementioned Ser. No. 228,740.

In effecting the present invention it is preferred to employ a permselective membrane as the cell divider, particularly a membrane which is permselective as to particles carrying a positive electric charge and which therefore permits the passage of cations, while preventing the passage of undesirable amounts of anions. Continuous, non-porous permselective cationic membranes comprising insoluble cation-exchange resin are suitable.

The cation-exchange resins which are preferred for use in such membranes are those of the sulfonic and carboxylic types, many of which are available commercially, such as sulfonated phenolaldehyde resin products, sulfonated cross-linked polymers of styrene, and carboxylic resins such as typified by those included in U.S. Patents Nos. 2,340,110 and 2,340,111, or any of the resins disclosed as suitable for such membranes in Jada et al., Reissue Patent 24,865. For example, a cationic membrane comprised of a sulfonated styrene-divinyl benzene polymer supported upon a glass fiber or fabric material can be employed. In general the cation permselective membranes employed comprise a solid polymeric matrix with at least 1 milliequivalent per dry gram of membrane

25 of dissociable ionic groups, e.g., acid groups such as carboxylate groups, fixed into said matrix, said membrane being reinforced by an embedded non-corrodible material. A suitable polymer of the indicated type is the sulfonated styrene-divinyl benzene copolymer described

30 under the name "Dowex 50" in the Journal of the American Chemical Society, volume 69, page 2830, (1947). Various other types of exchange materials can be employed, for example, porous film cast from a homogeneous mixture of 70-90% by weight of vinyl chloride-

35 acrylonitrile copolymer and 30-10% by weight of a water-soluble poly(vinyl benzyl trialkylammonium salt); membranes of sulfonated vinyl chloride polymers and copolymers; polyacrylic membranes and membranes of other olefinic acid polymers, and other addition polymers of

40 carboxylic acids, carboxylic anhydrides, carboxylic esters, carboxylic amides, carboxylic chlorides, carboxylic nitriles and other compounds which contain or can be hydrolyzed to carboxyl groups; membranes of condensation polymers of methylol forming sulfonated alkyl aryl ethers

45 with aldehydes, or of various sulfonated phenol-aldehyde resins. The membranes employed can be substantially homogeneous, uniform films of the ion exchange material, or can be uniform and intimate dispersions of such ion exchange material in a film or matrix of, for example,

50 a polymer of a perhaloethylene such as trifluorochloroethylene or tetrafluoroethylene; or the membranes can be particles of ion exchange material formed together by the same or a different type of resin or by water-insoluble jelly-like material such as petrolatum, amorphous wax, hydrocarbon jels, etc. It is preferred that the membrane

55 be substantially non-porous in order that it may be sufficiently permselective and will not permit too rapid movement of ions. It will be understood that the membranes must be reasonably resistant to attack by both anolyte

60 and catholyte solutions under conditions of operation and also that good mechanical strength is necessary for the embodiment in which there is highly turbulent liquid flow

65 over the membrane surface.

What is claimed is:

1. The method of electrolyzing acrylonitrile to obtain

and recover adiponitrile which comprises passing electric current through a catholyte in contact with a cathode, the catholyte consisting essentially of water, acrylonitrile and an electrolyte salt which has a discharge potential more negative than that of acrylonitrile and being separated by a diaphragm from the anolyte which is an aqueous acid solution having an acid concentration of 0.05 to 20% by weight, and of strength matched to the current density to provide sufficient hydrogen ion to neutralize hydroxyl ions generated at the cathode, and recovering adiponitrile from the catholyte.

2. The method of claim 1 in which the anolyte is an aqueous solution of an inorganic acid and the anolyte is separated from the catholyte by an ion exchange membrane.

3. The method of claim 1 in which the normality of the acid is in the range of 0.4 to 1.2 and the current density is in the range of 15 to 40 amperes per square decimeter.

4. The method of electrolyzing acrylonitrile to obtain and recover adiponitrile which comprises passing electric current through a catholyte in contact with a cathode, the catholyte being an aqueous electrolyte salt solution containing acrylonitrile, the electrolyte salt having a discharge potential more negative than that of acrylonitrile, and the catholyte being separated by an ion exchange membrane from the anolyte which is an aqueous acid solution of acidity such that the pH of the catholyte is maintained in the range of 7 to 9.5, and recovering adiponitrile from the catholyte.

5. The method of claim 1 in which the anolyte is an aqueous solution of an inorganic acid which is separated from the catholyte by a perm-selective cationic membrane and the electrolysis is conducted on a continuous basis involving addition of acrylonitrile to the catholyte and removal of adiponitrile from the catholyte during the

electrolysis without the necessity of adding materials to the catholyte to adjust the hydrogen ion concentration thereof.

6. The method of claim 5 in which the anolyte is an aqueous sulfuric acid solution.

7. The method of claim 6 in which the salt is a hydro-tropic quaternary ammonium salt.

8. The method of claim 1 in which the acid is sulfuric acid.

9. The method of claim 4 in which the cathode is composed of lead.

10. The method of electrolyzing acrylonitrile which comprises passing electric current through an aqueous quaternary ammonium sulfonate solution containing acrylonitrile in contact with a lead metal cathode, the said solution being separated by an ion exchange membrane from an aqueous acid of normality in the range of 0.4 to 1.2 in contact with an anode, the current density being in the range of 15 to 40 amperes per square decimeter and the acid being of strength matched to the current density to provide sufficient hydrogen ion to neutralize hydroxyl ions generated at the cathode, and recovering adiponitrile from the catholyte.
